UNITED STATES PATENT OFFICE.

ISIDOR KITSÉE, OF PHILADELPHIA, PENNSYLVANIA.

PROCESS OF PRODUCING MULTICOLORED SCREENS FOR PHOTOGRAPHY.

1,426,995.

Specification of Letters Patent. Patented Aug. 22, 1922.

Application filed January 17, 1919. Serial No. 271,710.

To all whom it may concern:

Be it known that I, ISIDOR KITSÉE, a citizen of the United States, residing at Philadelphia, in the county of Philadelphia and State of Pennsylvania, have invented certain new and useful Improvements in Processes of Producing Multicolored Screens for Photography, of which the following is a specification.

10 My invention relates to the process of producing multi-colored screens integral with photographic blanks, such for instance as moving picture films and I will describe here my invention as applied to moving picture films, it being obvious, that blanks for different photographic purposes may be substituted therefor.

I have discovered that it is possible to apply to a gelatine or like medium, with 20 which such blanks are usually provided, figurations of one color and then wash the whole blank with the aid of a second color, thereby tinting the free spaces between the figurations with a second color, without unduly interfering with the color of these figurations.

The accompanying drawing illustrates some forms my invention may take. In this drawing the Figs. 1, 2, 3, are plan views of 30 part of a film in different stages of producing thereon the multi-colored screen, and I elect here for this purpose, a color screen comprising the colors green and red.

I first produce on the surface of gelatine 35 or similar medium the figurations, here dots, colored green. These figurations may be applied to the gelatine or similar medium with the aid of rollers or other printing devices or with the aid of sprays or devices similar 40 in their action. In fact, for the purpose of my invention, it is immaterial through what means these figurations are applied to the gelatine film, so also is it immaterial for the purpose of my invention what form these 45 figurations may assume. But the nature of the solution has to be strictly adhered to.

In the course of my experiments I have discovered, that if a solution of dissolved resin is provided with the required color and 50 the figurations applied with this solution on the gelatine or similar film, no running or streaking of the color occurs and the figurations are clearly and sharply defined, by preference I use Canada balsam dissolved in 55 alcohol. I have also discovered, that if a dye-solution consisting only of the dye

proper dissolved in water is then applied to the film on which the figurations are placed, the figurations will not take up the color of this second solution, but the free gelatine 60 will readily be tinted with the color of this second solution.

To proceed therefore, in accordance with my invention, to produce the multi-colored screen it is only necessary to first apply the 65 figurations of the first solution onto the gelatine or similar film and then tint the uncolored spaces with the aid of the second solution by simply going over the whole film with a sponge or wad of cotton dipped in the 70 second solution, or the whole film may simply be immersed in this second solution, as neither the figurations, nor the celluloid out of which the film consists is injuriously affected by this second solution.

75 In the figures, illustrating one form of my invention, 1 is part of the film proper, 1^a the perforations with which these films are usually provided; 2 indicates the layer of gelatine or similar material, 3 the figurations, here represented by dots, and 4 the colored spaces between said figurations. The figurations are here illustrated as representing a green color and the free spaces between said figurations as being colored red, 85 it being obvious that other colors may be selected.

The figurations themselves, as well as the free area between these figurations are greatly exaggerated in size, so as to clearly 90 bring out the color of same, but in reality each of these figurations only occupy a very small part of an inch and the space between two of these figurations is of about like dimension.

95 The finished film should be washed, so as to remove the surplus color.

Having now described my invention, what I claim as new and desire to secure by Letters Patent is:—

100 1. The process of producing a multi-colored screen integral with a moving picture film which consists in producing figurations on the gelatinous substratum of said film with the aid of a colored alcoholic solution containing a dissolved resin and coloring the inter-spaces between said figurations with the aid of a dye insoluble in alcohol.

105 2. In the art of producing multi-colored screens integral with moving picture films 110 the improvement which consists in first producing figurations of one color on the gelat-

inous substratum of said film with the aid of an alcoholic dye-solution containing a dissolved resin, and then tinting the free spaces with the aid of a water-soluble dye.

- 5 3. In the art of producing multi-colored screens integral with moving picture films surfaced with gelatine, the method which consists in providing said gelatine first with one color with the aid of mechanical means
10 and then with a second color through the

process of immersing the whole film in a solution containing a second color, one of said colors miscible only in alcohol and one of said colors miscible only in water.

In testimony whereof I affix my signature 15
in the presence of two witnesses.

ISIDOR KITSÉE.
